UNITED STATES PATENT OFFICE.

FLORENCE E. TAYLOR, OF BOSTON, MASSACHUSETTS, ASSIGNOR OF ONE-THIRD TO EDWARD P. FORBES, OF BOSTON, MASSACHUSETTS.

LABEL-AFFIXING MACHINE.

No. 872,859.

Specification of Letters Patent.

Patented Dec. 3, 1907.

Application filed December 11, 1905. Serial No. 291,180.

To all whom it may concern:

Be it known that I, FLORENCE E. TAYLOR, of Boston, in the county of Suffolk and State of Massachusetts, have invented certain new and useful Improvements in Label-Affixing Machines; and I hereby declare that the following is a full, clear, and exact description of the same, reference being had to the accompanying drawings, forming part of this specification.

This invention has reference to improvements in machines for affixing labels to boxes and other articles.

One object of the invention is to so construct a label affixing machine that labels may be mechanically applied thereby to boxes, or other articles, suitably placed in the machine.

Another object of the invention is to so construct a label affixing machine that adhesive may be applied to the entire back of the label and that the entire label may be acted upon by presser devices to apply the label to the box or other article positioned to receive the same.

Another object of the invention is to improve the label feeding and glue applying devices together with the means for stripping the label from the glue applying device.

Another object of the invention is to so construct a label affixing machine adapted to apply glue, or other adhesive, to the entire back of the label that the label may be transferred from the glue applying means to the article to which it, the label, is to be affixed by positive means.

Another object of the invention is to so construct a label affixing machine that presser wipers may act on the entire surface of the label.

Other objects of the invention will appear from the following description and claims.

The invention consists in such peculiar features of construction and combination of parts as shall hereinafter be more fully described and pointed out in the claims.

Figure 1, represents a side elevation of the improved label affixing machine partly broken away, line 1—1 Fig. 4 to show the construction. Fig. 2, represents a rear view thereof. Fig. 3, represents an enlarged vertical sectional view of parts of the machine taken on line 3—3 Fig. 4. Fig. 4, represents a plan view of the machine parts of the same being broken away. Fig. 5, repre-

sents an enlarged isometrical view of parts of the label gripping and transferring mechanism. Fig. 6, represents an enlarged sectional view of parts of the label holder and the feeding device whereby the labels are periodically fed from said holder to the glue applying mechanism.

Similar numbers of reference designate corresponding parts throughout.

As shown in the drawings in its preferred form 5 indicates a base of substantial construction having thereon a main frame comprising the standards 6—6 and 7—7 suitably braced by cross members 8—8 and 9—9 connected by the vertical members as 10 and 11 supporting the table 11, Fig. 4. On the base 5 is also mounted the pedestal 12 to which is pivoted the foot lever 13 furnished with the rod 14 pivoted to said lever and having the collar 15 which bears against the expansion spring 16 mounted on said rod 14 and located between the collar 15 and a fixed part of the pedestal 12 whereby said spring 16 normally acts to draw upward the rod 15 and hold the clutch member 17, of any ordinary construction out of engagement with its coöperating clutch member forming part of the gear 18, the clutch member 17 being mounted on the shaft 19, to rotate therewith in any ordinary manner and the clutch member gear 18 being free, as to rotation, on said shaft 19 but being held from sliding thereon by the collar 20, the shaft 19 being journaled in bearings mounted on the cross members 8—8.

In bearings carried by the frame members 10—10 is journaled the main drive shaft 21 having the pulleys 22, 23, the sprockets 24 and 25 and the pinion 26 which meshes with the gear 18 so that when the shaft 21 is driven the gear 18 will also be driven without effecting the rotation of the shaft 19 unless the clutch member 17 be moved into engagement with its coöperating member of said gear 18 by the depression of the free end of the lever 13.

Mounted in the table 11 is the glue reservoir 27, adapted to contain glue or any other well known fluid adhesive, and in bearings mounted on said reservoir is journaled the shaft 28 having the gear 29 and carrying the glue applying roll 30 the periphery of which is furnished with a series of shallow annular grooves 31—31 which are approximately filled with glue, when glue is supplied to the 110

reservoir 27, whereby the surface of glue on the periphery of the roll 30 is not broken by these grooves in order that a label applied to the periphery of the glue roll may receive 5 glue over its entire surface, the object of the grooves 31—31 being that the inclined teeth of the comb or stripper 32, mounted on the glue reservoir 27, may engage beneath the edge of a label carried forward by the glue 10 roll. The gear 29 of the glue roll shaft is driven by the pinion 33 of the shaft 34 which is journaled in bearings below the table 11 and has the sprocket 35 to which motion is imparted by the chain 36 working over said 15 sprocket and over the sprocket 24 of the shaft 21.

At the feeding in side, or front, of the machine is mounted the side plates 37 and 38 which support a hopper formed of the inclined wall 39 having a thin lower edge, and the inclined bottom 40 having openings as 41 and projections as 42, Figs. 3 and 6. On this bottom 40 are adjustably mounted the guides 43—43 between which the labels are 25 fed forward. Journaled in bearings of the plates 37—38 are the shafts 44, 45 and 46; the shaft 44 has a series of disks 47—47 eccentrically disposed as regards the axis of their shaft and having peripheries of friction 30 material parts of which periphery work through the openings 41—41 of the hopper bottom at times calculated with reference to the desired feeding forward of the bottom label of a stack of labels in the hopper to feed 35 said label between the roll sections 48 and 49 respectively of the shafts 45 and 46. The shaft 44 has the sprocket 50 which is driven by the chain 51 working over said sprocket and over the sprocket 52 of the shaft 19; 40 the shaft 46 has the gear 53 which meshes with the gear 54 on the shaft 34; while the shaft 45 has the pinion 55 meshing with the gear 53' of the shaft 46. Above the shaft 45 is secured the plate 56 the edge of which extends close to the periphery of the glue roll 45 30, whereby a label thereon is smoothed out as it is drawn under the edge of said plate.

On the shaft 19 are mounted the cams 57—57 and 58—58; the cams 57—57 have 50 cam paths as 59, shown in full lines in Fig. 1 and the cams 58—58 have cam paths as 60 indicated in said figure in broken lines. Pivotally supported on the frames 6—6 are the levers 61—61 which have bearings as 62 55 adapted to work in the paths as 59 of the cams 57—57; at the upper ends of the levers 61—61 are pivoted connecting rods 63—63 which are respectively pivoted to the slides 64—64 mounted on guides 65—65 which are 60 secured at the sides of the machine near the rear thereof; on these slides 64—64 are fixed the inwardly extending members 66—66 beveled at their edges to form guides on which the blocks 67—67 are slidably mount- 65 ed for lateral adjustment; depending from

these blocks 67—67 are the fixed jaw members 68—68 having the lips 69—69 which extend towards the glue roll 30. In the jaw members 68—68 are journaled the shafts 70—70 on which are mounted the lips 71—71 70 which are adapted to coöperate with the lips 69—69 at times. The shafts 70—70 have crank arms 72—72 pivotally connected by the rods 73—73 with the plates 74—74 which are pivotally mounted on the slides 64—64; 75 as these slides 64—64 are reciprocated back and forth by the levers 63—63, and their connections, the lower ends of the plates 74—74 are moved between the pins 75 and 80 76 fixed in the machine; when the lower ends of the plates 74—74 strike the pin 75, in the forward movement of the slides 64—64 these ends of the plates are caused to swing backward and through the rods 73—73 to effect the rotation of the shafts 70—70 to close the 85 lips 71—71 towards the lips 69—69 to grasp the edge of a label in suitable position to be received between said lips while, when the slides 64—64 move backward sufficiently, the free ends of the pivoted plates 74—74 90 are intercepted by the pins 76—76 and are swung so as that by the connections with the shafts 70—70 these shafts are rotated to swing downward the lips 71—71 and release the label. 95

At the rear end of the machine on extensions from the standards 7—7 is the guide plate 77 on which are slidably mounted the blocks 78—79 in which are journaled the shafts 80 and 81 on which are mounted the 100 wiper presses 82 and 83 having the somewhat flexible wipers 84 and 85; the blocks 78 and 79 are moved inward and outward on the guide 77 by the connecting rods 86 and 87 pivotally mounted on the inner ends of 105 the shafts 80 and 81 and pivotally connected with the upper ends of the levers 88 and 89 which are mounted to swing on the frame members on which the guide 77 is supported and have the pinions 90 and 91. In vertical guides in the frame are movable the racks 92 and 93 which engage with the pinions 90 and 91 and, at their lower ends are pivotally connected by the links 94 and 95 with the corresponding ends of the levers 96 and 97 110 mounted to swing on the shaft 98, supported in the frame, and having at their other ends the bearings 99 and 100 which work in the paths respectively of the cams 58—58 which paths, as indicated in Fig. 1 of the 120 drawing are designed to swing the levers 94 and 95 upward and downward in succession to successively raise and lower the racks 92 and 93 to effect the successive sliding of the blocks 78 and 79 to move the same, and 125 their related wipers inward and outward.

Mounted on the rear ends of the shafts 80 and 81 are the crank arms 101 and 102 having projections which are free to slide in the grooves of the levers 103 and 104 which 130

levers are pivotally mounted on the member 105 centrally located on the guide 77 and have the arms 106 and 107 furnished with the roller bearings 108 and 109, and connected by the drawing spring 110.

The drive chain 111 works over the sprocket 25 on the shaft 19 and over the sprocket 112 of the sleeve 113 furnished with the sprocket 114 and rotatable on a stud extending from the upper portion of the frame. On the guide 77 are mounted the bearings 115 and 116 in which the shaft 117 having the disk 118 with its cams 119, 120 and 121, and the sprocket 122 is journaled; the chain 123 working over the sprockets 114 and 122 transmitting motion to the shaft 117 to drive the same.

Mounted for vertical movement in a guide of the bearing block 115 is the spring pressed rod 124 having a roller bearing 125 at its upper end which is pressed against the periphery of the cam disk 118 by the spring 126 located between a shoulder on said rod and a fixed part of the machine frame whereby a constant pressure is exerted by said spring 126 to lift said rod and the clamping plate 127, on the lower end thereof, away from the central supporting member 128 mounted on the guide 129 which is carried by the frame 30 and located near the comb 32. On this guide 129 are slidably mounted for lateral adjustment the form members 130—130 shaped to support the box or other article to which a label is to be affixed. Glue, or other fluid adhesive, being placed in the reservoir 27 the shaft 21 is driven by any ordinary belt working on one of its pulleys 22—23, this motion of the shaft 21 being transmitted to the shaft 34 by the chain 36, working over the sprockets of these shafts, whereby the shaft 34 and the mechanism connected therewith by the gears 33, 29, 54, 53 and 53' is driven, this mechanism including the glue roll 30, whereby the glue in the reservoir is mixed and a thin film of the glue is taken up by the periphery of the glue roll; at the same time the shafts 45 and 46 of the feed rolls 48 and 49 are driven, while the pinion 26 on said shaft 21 drives the loose gear 18 on the shaft 19. A pile of labels is now placed on the plate 40, between the guides 43—43, the printed surfaces of the labels being uppermost, these labels are pushed forward on the plate 40 until they meet the inclined plate 39 which from its inclination permits the lowermost of the labels to extend beyond the upper labels and tends to press downward the labels as they are moved forward. A box is then placed on the form members 128—130—130 to support one end of the box in position to receive the label, and boxes are successively placed, on and removed from, said combined form members during the feeding forward of the labels supplied with glue. When the lever 13 is pressed down

ward at its free end the rod 15 is actuated to bring the clutch member 17 into engagement with the clutch member of the gear 18, thus connecting this gear with the shaft 19 whereby said shaft and the mechanism in driving connection therewith is driven from the pinion 26 on the shaft 21.

Following the operation as it progressively acts on the labels it will be seen that, as the shaft 44 is rotated, by the connections above described, its cam sections 47 will swing through the openings 41 of the plate 40 and the peripheries of said sections will frictionally engage the under surface of the lowermost label, and will carry said label forward between the rolls 48 and 49 between which the label will be fed to the periphery of the glue roll 30. The forward edge of the label being first applied to the glue surface on this roll 30 will be drawn forward with the roll 85 and will first pass under the edge of the plate 56 whereby the label is smoothed down on to the glue surface of said roll and glue is applied to the entire back of the label. When the forward edge of the label reaches 90 the doffer comb 32 it will be stripped from the glue roll, but the ends of the teeth of the comb extending beneath the label, the latter will be in a position to be grasped by the jaws of the label transferring mechanism. 95

The action of the cams 57—57, on their levers 61—61, is so timed with relation to the delivery of the labels to the comb 32 that, as a label is so delivered, the levers 61—61 are swung to draw forward the rods 100 63—63 and the slides 64—64 with their members 67 carrying the grasping jaws the lips 71—71 of which are opened away from the lips 69—69. When these jaws are carried sufficiently forward to receive the edge 105 of a label positioned on the comb 32, the plates 74—74 strike the pins 75—75 and swing backward to rock the shafts 70 and close the lips 71—71 towards the lips 69—69, thus grasping the edge of the label between 110 said lips. Approximately at this time the cams 57—57 act to swing the levers 61—61 backward, thus effecting the backward movement of the slides 64—64 and their jaws with the glued label until the label is drawn 115 over the end, or side, of the box, located on the form members 128—130—130, when the plates 74—74 strike the stops 76—76 and effect the rocking of the shafts 70—70 to swing the lips 71—71 away from the lips 120 69—69 to release the label.

At or about the time the label is brought over the box the cam disk 118 has been rotated to a point where its cam 121 begins to bear against the roller bearing 125 on the rod 124 to force downward said rod and its clamping plate 127 against the action of the spring 126, the lower edge of the plate 127 bearing transversely on the central portion of the label. During the downward move- 130

ment of the clamping plate 127 the rack 92 is drawn downward by the swinging of the lever 96, actuated by its cam 58, to swing inward the arm 88 and the block 78 connected thereto to carry the free edge of the wiper 84 close to the side of the clamp plate 127; the cam 119 now acts against the roll 108 to swing outward the upper end of the arm 106, thus swinging the arm 103 downward and effecting the downward swinging of the presser 82 to bring the wiper 84 against the label on the box. The arm 88 is now drawn outward by the action of its driving connections and the wiper 84 is drawn outward 15 with its block 78 and wipes this end of the label smoothly on the box.

Approximately at the time the wiper 84 is moved outward from the clamp 127 the cam 121 passes the bearing 125 and the 20 clamp plate is raised by the spring 126 while the wiper 85 and its block 79 are moved inward by the swinging of the arm 89, which arm being somewhat longer than the arm 88 moves the block 79 inward farther than the block 78 was moved and carries the edge of the wiper 85 inward beyond the path in which the clamp plate 127 moves, thus when the cam 120 is brought to bear against the bearing 109 arm 107 is 25 swung outward and the arm 104 moves downward to bring the edge of the wiper 85 to bear on a portion of the label beyond the line of the clamp plate 127 and to the point at which the edge of the wiper had previously 30 began its wiping action on the label. After being thus swung downward the wiper 85 and the block 79 are drawn outward by the outward swinging of the arm 89, the edge of the wiper pressing downward and smoothing the part of the label over which it works, 35 in this movement. After the affixing of a label to one box, said box is removed from the forms 128—130—130 and another box is placed in position.

45 While I have herein described specific forms of mechanism, and specific combinations of parts, whereby the objects of the invention are carried into practice, it is not my intention to thereby limit my invention 50 to such specific features.

Having thus described my invention, I claim as new and desire to secure by Letters Patent:

55 1. A label affixing machine comprising a glue roll having a series of slight annular depressions, means for rotating said roll, means for supplying glue to the periphery thereof, a smoother plate having an edge located near the roll, means for feeding labels to said roll beneath said smoother plate, and means extending into said depressions for stripping labels from said roll.

60 2. A label affixing machine comprising glue applying means, a guide located at one side of said means, a slide movable on said

guide for adjustment, a jaw fixed to said slide, a shaft journaled in said jaw and having a lip thereon, means for rotating the shaft, and means for reciprocating the guide.

3. A label affixing machine comprising 70 guides, slides movable on said guides and having laterally extending guide members, blocks adjustable on said guide members and having fixed jaws shafts journaled in said jaws and having lips complementary to said 75 jaws and crank arms, plates pivotally mounted on the first mentioned slides, means for moving said slides and means for intercepting the free end of the pivoted plate as and for the purpose described. 80

4. In a label affixing machine, the combination with a support for the article to which a label is to be applied, a clamp movable towards and from said support and adapted to bear against the central portion 85 of the label whereby the surface of the label at the sides of said clamp are exposed for the action of pressers, and means periodically moving said clamp towards and from said support, of a pair of wipers, and means for 90 operating said wipers in succession, one of said wipers being mounted to swing across the path of said clamp as described.

5. In a label affixing machine, the combination with a support for the article to be 95 labeled, of a pair of wipers mounted to slide and swing above said support, and means for alternately operating said wipers to wipe against the label from the central portion towards the ends. 100

6. In a label affixing machine, the combination with a support for the article to be labeled, a clamp movable towards and from said support, and a pair of wipers pivotally mounted on means movable towards and 105 from the path of the clamp, of means for operating one of said wipers while the clamp is in the depressed position, means for moving the clamp away from the support and means for subsequently operating the second wiper. 110

7. In a label affixing machine, the combination with means for supporting the article to be labeled, a clamp mounted to move towards and from said support, and a cam for operating said clamp of a lateral guide, 115 slides movable on said guide, shafts pivotally mounted in the slides, wipers mounted on said shafts, means for reciprocating the slides and means for effecting the partial rotation of the shafts.

8. In a label affixing machine means for pressing the label in place comprising a pair of wipers pivotally mounted in sliding members, and having crank arms furnished with pins, pivoted guides in which said pins are 125 engaged, means for operating the sliding members, and means for swinging the pivoted guides.

9. In a label affixing machine, the combination with a support for the article to be 130

labeled, a transverse guide above said support, a spring lifted clamping device centrally mounted on said guide, a cam disk rotatably mounted above said clamping device and having a peripheral cam, adapted to act thereagainst, and alternately disposed side cams, a pair of blocks slideable on said guide, means for reciprocating said blocks, shafts journaled in the blocks and having 5 cranks, wipers mounted on the shafts and a 10 pair of guides, pivotally mounted on the

transverse guide, in which the cranks of said shafts are engaged, and having spring retracted lever arms adapted to be operated by the side cams of said cam disk, as and for the 15 purpose described.

In testimony whereof I affix my signature in presence of two witnesses.

FLORENCE E. TAYLOR.
